(57) **CLAIM**

We claim the ornamental design for a wristband health tracker, as shown and described.

DESCRIPTION

FIG. 1 is an isometric view of a wristband health tracker looking at the top, front, and right sides.

FIG. 2 is a further isometric view of the wristband health tracker looking at the top, back, and right sides.

FIG. 3 is a further isometric view of the wristband health tracker looking at the bottom, back, and left sides.

FIG. 4 is a further isometric view of the wristband health tracker looking at the bottom, front, and left sides.

FIG. 5 is a left side view of the wristband health tracker.

FIG. 6 is a right side view of the wristband health tracker.

FIG. 7 is a front view of the wristband health tracker.

FIG. 8 is a back view of the wristband health tracker.

FIG. 9 is a bottom view of the wristband health tracker.

FIG. 10 is a top view of the wristband health tracker; and, FIG. 11 is an isometric view of the wristband health tracker looking at the top, front, and right sides.

Dashed and dotted lines are used for illustrative purposes only to give environmental context to the claimed design and do not form any part of the claimed design.

Stipple shading is used in FIGS. 1 through 11 to convey surface contouring and is to be understood as not conveying a particular surface finish. Translucent, clear, or clear, tinted material is indicated by diagonal line hatching, as is visible in the square area shown in FIGS. 1, 2, 7, 10, and 11.
